(57) **CLAIM**

The ornamental design for a wet wipe dispenser, as shown and described.

DESCRIPTION

FIG. 1 is a perspective view of the wet wipe dispenser showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

Broken lines are included for depicting environmental subject matter and form no part of the claimed design.

1 Claim, 6 Drawing Sheets(56)
